UNITED STATES PATENT OFFICE

154,118

DESIGN FOR A SCARF

Rose Gottschalk, New York, N. Y., assignor to Edgar C. Hyman Co., Inc., New York, N. Y., a corporation of New York

Application May 25, 1948, Serial No. 146,592

Term of patent 3½ years

(Cl. D3—12)

To all whom it may concern:

Be it known that I, Rose Gottschalk, a citizen of the United States of America, and a resident of New York, in the county and State of New York, have invented a new, original, and ornamental Design for a Scarf, of which the following is a specification, reference being had to the accompanying drawing, forming a part thereof.

The figure is a plan view of a scarf, showing my new design, one quarter of which is shown in full lines. The other three-quarter sections are identical therewith and are arranged in proper relation to complete the scarf.

A portion of the border, which is composed of appropriate repetition of the elements disclosed, is omitted for convenience in illustration.

I claim:

The ornamental design for a scarf, substantially as shown and described.

ROSE GOTTSCHALK.
